[57] CLAIM

The ornamental design for a seat, as shown and described.

DESCRIPTION

FIG. 1 is a front perspective view of a seat in the form of a chair embodying our new design;

FIG. 2 is a front elevational view of our new design;

FIG. 3 is a top plan view of our new design;

FIG. 4 is a rear elevational view of our new design;

FIG. 5 is a front perspective view of a seat in the form of a love seat showing a second embodiment of our new design;

FIG. 6 is a front perspective view of a seat in the form of a sofa showing a third embodiment of our new design; and,

FIG. 7 is a side elevational view of the various embodiments of our new design, the opposite side of each embodiment being substantially a mirror image thereof (with or without the handle shown in phantom).

The broken line showing of an adjustment mechanism in FIGS. 1, 5, 6 and 7 is for environmental purposes only and forms no part of the claimed design.

The rear views of the love seat and sofa embodiments form no part of the claimed design.
